CLAIM

The ornamental design for a battery pack converter, as shown and described.

DESCRIPTION

FIG. 1 is a first perspective view of a battery pack converter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The dash-dash broken lines in the drawings illustrate portions of the battery pack converter. The dash-long dash broken lines in the drawings illustrate the boundaries of the enlarged views. None of these broken lines form part of the claimed design.
